UNITED STATES PATENT OFFICE.

JOHN COLLINS, OF HIGHLANDVILLE, MASSACHUSETTS.

DESIGN FOR KNITTED MITTEN.

SPECIFICATION forming part of Design No. 12,064, dated December 21, 1880.

Application filed October 30, 1880. Term of patent 14 years.

To all whom it may concern:

Be it known that I, JOHN COLLINS, of Highlandville, in the county of Norfolk and State of Massachusetts, have originated and designed a Connected Mitten and Wristlet, of which the following is a full, clear, and exact description, reference being had to the accompanying photographic illustration, making part of this specification.

10 In this my design for a mitten that part of the mitten marked *a*, just above the line 1 and the hand part *b*, is contracted or curved inwardly. Above this part, and between the lines 2 2 and 3 3, the part *d* of the mitten is 15 enlarged or bulged outwardly, and from the line 3 3 to the line 4 4 the part *f*, which forms a continuation of the parts *a* *d*, is contracted in size to be smaller than the part *d*.

The part *d*, instead of being composed of a 20 plain ribbed knitted web, is so knitted as to form annular ribs or bands 5 6 7 8, the said ribs being thrown up by knitting in the manner practiced when forming tucks.

The part *d* of the mitten is ornamented by 25 annular stripes or bands 9 10 11 12 13, showing yarn or thread contrasting in color or material, or both, with the yarn forming the hand part *b*, the ornamented thread so thrown into the part *d* representing a zigzag more or less 30 sharp or waved.

At the top of the part *f* is an annular ornamented band, 14, and the part *d* is further ornamented by the small rings 15.

My design for a mitten, as herein described, 35 has a peculiar outline when viewed upon its upper side, as in the photograph, enabling it to be distinguished from any other mitten

heretofore known to me or in the market, and it is also peculiar in its stripes or annular bands containing stitches of a color different 40 from the main threads of the mitten.

I claim—

1. A design for a knitted mitten, it including an outline showing a hand part, *b*, an inwardly-curved or contracted portion, *a*, above 45 it, and the outwardly-bulged or enlarged portion *d*, as shown.

2. As a design for the outline of a mitten, the hand part *b*, the inwardly curved or contracted part *a*, the outwardly curved or bulged 50 part *d*, and the contracted longer portion *f* beyond part *d*, as shown.

3. In a design for a knitted mitten, the bulged part *d*, having a series of enlarged annular ribs, 6 7, thrown up above the level of 55 the adjacent knitting, substantially as shown.

4. In a design for a mitten, the hand part *b*, contracted or inwardly-curved part *a*, the bulged part *d*, and the annular stripe 9 above 60 the part *a*, as shown.

5. As a design for a mitten, the hand part *b*, contracted part *a*, bulged part *d*, ornamented by stripes or bands composed of yarn or threads of different colors, and the part *f*, ornamented by the addition to it of annular stripes of yarn 65 or threads of different colors, substantially as shown.

In testimony whereof I have signed my name to this specification in the presence of two subscribing witnesses.

JOHN COLLINS.
